UNITED STATES PATENT OFFICE.

JAMES EDWARD WYCKOFF, OF ROCHESTER, NEW YORK.

TELEPHONE ATTACHMENT.

Application filed August 17, 1925. Serial No. 50,796.

This invention relates to attachment for telephones, particularly pay-station telephones.

An object of the invention is to provide a simple and efficient attachment which will prevent the signal within the telephone box from being operated whenever a light-weight coin or check is inserted in the chute or coin-slot.

10 A further object provides a simple and efficient attachment which can be disposed within the coin-box without requiring any substantial alteration of the construction of the box and the parts originally disposed 15 therein.

The invention is illustrated in the drawings of which Figure 1 is a rear elevation with a portion cut away showing the interior construction of a coin-box of a pay telephone. Figure 2 is a section taken on the line 2-2 of Figure 1.

The form of the invention shown in the drawings is a preferred form, although it is understood that modifications in the construction and arrangement of the parts and in the character of the materials used may be adopted without departing from the spirit of the invention as set forth in the appended claim.

30 Whenever a person uses a pay telephone and inserts a lightweight check in the coin-chute, this check passes down the chute and at a certain portion of its travel normally comes into contact with a signal device to 35 sound the same after which it proceeds on its way. Often times instead of using legitimate coins of the proper weight, the dishonest people will use lightweight coins or substitutes therefor. In some cases the metal 40 rim Dennison tag checks are sometimes used instead of a silver quarter in the pay telephone.

I aim to overcome the difficulty by disposing within the box adjacent the gong or signal device, a flexible member which is 45 disposed in the path of the coin or check and has sufficient resistance to prevent a

fraudulent or lightweight check from operating the gong or signal, but not having sufficient resistance to prevent a coin of proper weight from operating the signal.

This flexible baffle member as I may call it may be in the form of a spring strip or it may assume many other shapes the broad idea being that it has sufficient resistance for 55 the purposes above set forth and that it is disposed adjacent the gong and in the path of the check.

In the preferred form of the invention shown in the drawings I illustrate a pay 60 telephone box 10, with the coin or check chute shown in dotted lines. This chute is formed within a frame 12. Fastened at any suitable point within the box is a flexible baffle device 13 preferably shown in the form 65 of a coil spring, which as shown in Figure 2 can be fastened to the casing 14 of the box by the screw 15 and have its end 16 disposed in the path of the check as it travels 70 down the chute 11. This baffle member is disposed adjacent a gong 17 and between the gong and the chute, so that as the coin travels down the chute it will come in contact with the baffle member before it can 75 possibly contact with the gong or signal.

The flexibility of the baffle member 13 is such that any check which is under normal weight will be successfully resisted by the baffle member to prevent contact with the gong; whereas the flexibility of the baffle 80 member is such that a normal or overweighted coin or check will operate the gong.

What I claim is:—

An attachment for pay telephones having a signal device and a check chute which comprises a spring blade mounted within the casing of the telephone in front of the signal device and in such relation to the check chute as to cause the check to come in contact with it before contact with the signal 85 device, the resiliency of the spring being pre-determined to prevent the actuation of the signal device by lightweight checks.

JAMES EDWARD WYCKOFF.
